UNITED STATES PATENT OFFICE.

HIRAM S. HEARN AND ARNOLD E. PERRETE, OF DENVER, COLORADO.

TOOTHPICK-DISPENSER.

1,390,553.

Specification of Letters Patent. Patented Sept. 13, 1921.

Application filed April 12, 1920. Serial No. 373,226.

To all whom it may concern:

Be it known that we, HIRAM S. HEARN and ARNOLD E. PERRETE, citizens of the United States, residing at Denver, in the 5 county of Denver and State of Colorado, have invented certain new and useful Improvements in Toothpick-Dispensers, of which the following is a specification.

This invention relates to an improved 10 tooth pick dispenser and has as one of its principal objects to provide a device of this character wherein the supply of tooth picks will be housed and protected from dust and dirt while the tooth picks will be delivered 15 singly so that the device will thus insure a sanitary condition of the tooth picks.

The invention has as a further object to 20 provide a device requiring a separate actuation thereof for each tooth pick delivered, to the end that this feature, in conjunction with the fact that the tooth picks are delivered singly, will tend to discourage waste of the tooth picks.

The invention has as a further object to 25 provide a device which will be dependable for delivering a single tooth pick each time the device is actuated and wherein liability of jamming of the tooth picks or mutilation thereof will be reduced to a minimum.

30 And the invention has as a still further object to provide a device which will be neat and attractive and which will accordingly, when installed, provide a desirable ornament.

35 Other and incidental objects will appear hereinafter:

In the drawings:

Figure 1 is a perspective view of our improved tooth pick dispenser,

40 Fig. 2 is a fragmentary vertical section taken medially through the device,

Fig. 3 is a sectional view taken at substantially right angles to Fig. 2, on the line 3-3 of Fig. 2, and

45 Fig. 4 is a fragmentary vertical section showing the tooth pick hopper of the device depressed.

In carrying the invention into effect, we 50 employ a base 10 which may be formed of wood or other approved material and upstanding from this base are spaced vertical guide posts 11 on the upper ends of which are threaded nuts 12. Between said posts and in alignment therewith is arranged an 55 upstanding ejector 13. This ejector is in

the nature of a flat plate which may be integral with the base or otherwise secured thereto and formed in the upper end edge of the ejector is a tooth pick receiving slot 15 having parallel side walls. Preferably, 60 this slot is only of a width to receive either one edge portion or the other of a tooth pick so that a tooth pick falling into the slot must lie therein upon one of its longitudinal edges. As particularly brought out in Fig. 65 3, the upper end of the ejector is provided with beveled faces sloping in opposite directions from the slot, and formed in the upper end portion of the ejector are spaced vertical notches 16 opening through the upper end of the ejector.

Between the guide posts 11 is a vertically 70 shiftable tooth pick hopper 17. This hopper is preferably cylindrical and is normally closed by a spring pressed door 18 which 75 forms a part of the cylindrical wall of the hopper. However, as will be observed, a slot 19 is provided in the upper side of the hopper at the free edge of the door. Projecting from the end walls of the hopper 80 are lugs 20 freely receiving the guide posts therethrough so that these lugs thus slidably support the hopper upon the posts, and bearing beneath said lugs are helical elevating springs 21 for the hopper, these springs surrounding the guide posts and resting at their lower ends upon the base 10. Opposed to the elevating springs are helical cushioning springs 22 for the hopper, these latter 85 springs surrounding the upper end portions 90 of the posts and bearing against the upper sides of the lugs. Housing the springs 21 and 22 are tubular casings 23 receiving the guide posts through the upper end walls thereof and resting at their lower ends upon the base 10, the casings being secured by the nuts 12 upon the upper ends of the posts and being slotted at their inner sides to 95 freely receive the lugs 20 therein. Thus, it will be seen that the hopper may be depressed against the action of the springs 21, and to facilitate this operation the hopper 100 is preferably provided with a finger rib. Upon release of the hopper, said springs will immediately return the hopper to its 105 normal position, when the springs 22 will operate to cushion the hopper in its upward movement.

Depending from the hopper 17 is a sleeve 24 snugly but slidably fitting over the ejector 110

13 so that fragments of tooth picks or other foreign matter can not enter between the sleeve and ejector to cause sticking of the hopper. When the hopper is in its normal 5 elevated position, this sleeve forms a feeding slot 25 above the upper end of the ejector. Upstanding from the curved wall of the hopper at one side of the slot 19 are resilient 10 delivering fingers 26, and coacting with these fingers are similar fingers 27 upstanding from the free longitudinal edge of the door 18. As particularly brought out in Fig. 3, the lower end portions of the fingers converge upwardly over the slot while 15 the upper end portions of the fingers are slightly divergent.

In use, the hopper is filled preferably about half full with a supply of tooth picks. As will be seen, one or more of the tooth picks 20 will always gravitate into the slot 25 so that when the hopper is in its normal position, a tooth pick will be lodged within the groove 15 of the ejector. Consequently, when the hopper is then depressed to project the 25 ejector through the slot 19 of the hopper, the tooth pick so lodged in the slot 15 will be exposed at the upper side of the hopper. In this connection, it is to be observed that the beveled faces at the upper end of the 30 ejector will prevent lodgment of more than one tooth pick upon the ejector. As the hopper approaches the limit of its downward movement, the upwardly converging lower end portions of the pairs of delivering 35 fingers will move into the notches 16 of the ejector beneath the tooth pick thereon and, as will be particularly observed upon reference to Fig. 4, the inclined portions of the fingers 27 are adapted to ride against the 40 bottom walls of said notches for slightly swinging the door 18 and consequently moving the fingers 26 away from the fingers 27 as the hopper reaches the limit of its downward movement. This slight spreading of 45 the fingers is desirable in order that the tooth pick may, should it have been disturbed in its position, settle back into the groove 15. Consequently, when the hopper is released, as shown in Fig. 1, and the hopper 50 is moved upwardly by its elevating springs, the fingers 27 will, upon being shifted out of engagement with the bottom walls of said notches, be moved toward the fingers 26 for clamping the tooth pick between said fingers, it being observed that the tooth pick will lie upon the ejector in such manner that the fingers will engage the flat sides of the tooth pick. The tooth pick will thus be carried upwardly with the hopper 55 and supported in such position by the fingers that the tooth pick may be easily

grasped and removed. The device will, therefore, operate each time the hopper is depressed, to deliver a single tooth pick while the supply of tooth picks will be kept in a clean condition within the hopper. Since the feeding slot 25 is located directly at the bottom of the hopper the tooth picks will readily slide into said slot while, when the hopper is depressed, the presence of the 65 ejector within the hopper will tend to straighten the tooth picks. Further, when the hopper is released and moves upwardly to strike the cushioning springs 22, the resultant vibration of the hopper will also 70 tend to straighten and feed the tooth picks 75 into the feeding slot of the hopper.

Having thus described the invention, what is claimed as new is:

1. In a tooth pick dispensing device, the 80 combination of a base, guide posts rising therefrom, an ejector upstanding from the base, a hopper slidably supported by said posts and depressible over the ejector, springs surrounding the posts and normally 85 acting to hold the hopper elevated, springs carried by the posts for cushioning the hopper in its upward movement, and delivery means carried by the hopper to engage a tooth pick upon the ejector.

2. In a tooth pick dispensing device, the 90 combination of a fixed ejector, a hopper depressible over the ejector, yieldable means for moving the hopper upwardly, yieldable means for cushioning the hopper in its up- 95 ward movement, and delivery means carried by the hopper to engage a tooth pick upon the ejector.

3. A device of the character described including a base, guide posts rising therefrom, 100 an ejector upstanding from the base between said posts, a hopper slidably supported by said posts and depressible over the ejector, springs surrounding the posts and normally holding the hopper elevated, casings housing 105 said springs, and means upon the upper ends of the posts securing the casings and limiting the hopper against upward displacement.

4. In a tooth pick dispensing device, the 110 combination of a fixed ejector, guide posts, a hopper depressible over the ejector and slidably supported by said posts, yieldable means carried by the posts and sustaining the hopper, yieldable means carried by the 115 posts for cushioning the hopper in its upward movement, and a casing upon the posts housing all of said yieldable means.

In testimony whereof we affix our signatures.
